(57) **CLAIM**

The ornamental design for a badge mount for a license plate frame, as shown and described.

DESCRIPTION

FIG. 1 is a right front perspective view of a badge mount for a license plate frame showing our design;

FIG. 2 is a front view thereof;

FIG. 3 is a top view thereof;

FIG. 4 is a bottom view thereof;

FIG. 5 is a right side view thereof; and,

FIG. 6 is a left side view thereof.

The portions of the drawings shown in broken lines represent environmental structure and form no part of the claimed design.
